UNITED STATES PATENT OFFICE.

RALPH HAZLETT UPSON, OF AKRON, OHIO, ASSIGNOR TO THE GOODYEAR TIRE AND RUBBER COMPANY, OF AKRON, OHIO, A CORPORATION OF OHIO.

APPARATUS FOR HEATING INFLATING-GAS IN BALLOONS.

1,096,578.

Specification of Letters Patent.

Patented May 12, 1914.

Application filed January 29, 1913. Serial No. 745,025.

To all whom it may concern:

Be it known that I, RALPH HAZLETT UPSON, a citizen of the United States, residing at Akron, in the county of Summit and State of Ohio, have invented new and useful Improvements in Apparatus for Heating Inflating-Gas in Balloons, of which the following is a specification.

This invention relates to apparatus for artificially heating the gas used in balloons, especially of the dirigible type.

Briefly, in large balloons, especially of the dirigible type, the volume of gas is, of course, increased by heat and reduced by cold, and hence, when the balloon is in use and the sun shines upon the gas bag of the balloon the latter is heated, thereby expanding the gas and increasing its lifting capacity, and when the sun is obscured the lifting qualities of the gas in the balloon is decreased. It therefore becomes extremely desirable to maintain the temperature of the gas as nearly constant as possible to thereby maintain the vertical equilibrium of the balloon.

It will be obvious that as the gas generally employed for inflating balloons is hydrogen, and is highly inflammable, the means for artificially heating the same must be of such a nature as will render the employment thereof absolutely safe.

More specifically, this invention contemplates withdrawing a portion of the gas from the balloon and passing it through a conduit containing a heat generating means and returning it to the balloon at a higher temperature than when withdrawn from the balloon. The means employed for heating the gas is so arranged as to be rendered operative at will. This invention more particularly contemplates the employment of the waste heat from the radiator of the motor employed for propelling the balloon as the means most readily available for accomplishing this purpose.

With the foregoing and other objects in view, the invention consists in the novel construction, combination and arrangement of parts constituting the invention to be hereinafter specifically described and illustrated in the accompanying drawings which form a part hereof wherein is shown the preferred embodiment of the invention, but it is to be understood that changes, variations and modifications can be resorted to which come

within the scope of the claims hereunto appended.

In the drawings in which similar reference numerals indicate like parts in the different figures, Figure 1, is a diagrammatic view of the lower wall of a dirigible balloon showing the mechanism by which the heating of the inflating gas is accomplished; and, Fig. 2, is a view enlarged and partly in section of the heating apparatus and the valve mechanism connected therewith.

Referring to the drawings in detail, the reference numeral 1 denotes a portion of a balloon provided with a lower wall 2 of suitable material and depending from which are conduits 3 and 4, the interiors of which are in open communication with the interior of the balloon. The conduits 3 and 4 extend downwardly and are curved so that their ends oppose each other but are separated from each other for the interposition of mechanism for heating the gas passing from one conduit to the other and from one portion of the balloon to the other. These conduits will preferably be formed of flexible fabric rendered fluid-tight by a special process which forms no part of this invention. It will be stated for brevity that the opposing ends of the conduits 3 and 4 are similarly equipped and furnished with identical mechanism so that the description of one will suffice for both. Surrounding the end of the conduit 4, for illustration, is a ring 5 L-shaped in cross section, formed of wood for lightness, and inclosed on one side by a thin metallic covering 6. Secured to the lateral face of the ring 5 is a ring 7 of wood or other light material, inclosed by a thin covering of metal of tubular formation and secured to the ring 5 through the medium of bolts 8. The open end of the conduit 4 is secured to the ring 5 or, if desired, may be clamped between the members 5 and 7 by the bolts 8 for forming a fluid-tight joint therewith. The metal covering 9 on one side of the ring 5 is provided with an outwardly projecting integrally-formed annular rib 10 for a purpose to be later described. The inner lateral portion of the ring 5 at the right in Fig. 2, is not protected by metal and is provided with an annular groove 11 constituting a valve-seat. Secured to the inner left-hand wall of the covering 9 of metal surrounding the ring 5 are a plurality of brackets 12 to each of

which is pivotally united a link 13 and to which a link 14 is hinged at 15 and each pair is further connected by a resilient element 16. The opposite end of each link 14 is pivotally connected to an ear 17 on the inner face of a dish-shaped valve 18, the edge of the open portion of which is adapted to seat in the annular groove 11 in the member 5 and close the opening formed by 10 said member. The normal tendency of the resilient elements 16 is to shift each valve 18 to its closed position as shown in the right in Fig. 2. In this figure, the position of one of the valves in its open position is 15 indicated by dotted lines on the left of the figure. Secured to the outer faces of the metallic covering 9 on one side of the ring 5 are a plurality of brackets 19 to which are pivotally connected levers 20 provided with 20 pivot-pins 21. In practice, it is customary to employ a plurality of these levers 20 for a purpose to be later described.

The rings 5 on the opposing ends of the conduits 3 and 4 will be separated from each 25 other and between them is interposed the mechanism for controlling the temperature of the gas passing through the conduits 3 and 4 from one portion of the balloon to the other. This mechanism consists of a cylindrical shell or casing 22 in both ends of which are placed rings 23 preferably of some light material such as wood and provided with annular grooves 24 forming seats into which the ridges 10 of the rings 5 are 30 adapted to seat when the rings 5 and 23 are brought into juxtaposition and this latter operation is accomplished through the following mechanism: Secured on the outer metallic coverings 25 of the rings 23 are a plurality of apertured brackets 26 to which are pivotally connected links 27 which are pivoted on the pivot-pins 21, so that through the manipulation of the outer free ends of the levers 20 the annular ridges 10 are 35 tightly seated in the annular grooves 24 for effecting a fluid-tight joint between the interiors of the conduits 3 and 4 and the interior of the casing 22. It will, of course, be obvious that the means for causing the engagement between both ends of the casing 22 and the ends of the tubular conduits 3 and 4 are similar in all respects.

Fixedly secured on an inverted U-shaped supporting frame 28 within the casing 22 is 55 a radiator 29 which is normally heated by the motor used for propelling the balloon and is cooled if desired through the medium of water which is introduced through a pipe 30. Extending across the upper end of the 60 casing 22 and preferably attached at their opposing ends to the radiator are a pair of diaphragms 31 and 32 each of which is provided with minute apertures 33. Extending from the lower portion of the radiator 29 65 to the wall of the casing 22 are perforated

diaphragms 34 and 35. The object and function of these diaphragms will appear later.

Secured in a bearing 36 in the wall of the casing 22 and also in a bearing 37 attached 70 to the supporting frame 28 is a rotatable upright shaft 38 to the upper end of which is secured a bevel-gear 39. Below the bevel gear 39 is an L-shaped housing 40 the upper end 41 of which constitutes a bearing for a 75 horizontally rotatable shaft 42 the opposite end of which is rotatably mounted in a bearing 43 within the radiator 29. Mounted on the shaft 42 is a bevel-gear 44 meshing with the bevel-gear 39 to be rotated by 80 the latter. Mounted on the shaft 42 is a fan 45 the function of which is to drive fluid within the casing 22 through the radiator 29 for heating it. Arranged in open communication with the upper portion of the 85 interior of the casing 22 above the diaphragms 31 and 32 is a pipe 46 and below the diaphragms 34 and 35 and in open communication with the interior of the casing is a pipe 47.

Referring now more particularly to Fig. 1, the pipes 46 and 47 communicate with a valve-casing 48 which is also provided with an inlet pipe 49 communicating either with the balloon or with one of the tubular 95 conduits, and the casing 48 is further provided with an exhaust pipe 50, and an inlet pipe 51 for air under pressure and this pipe is provided with a check valve 52. Within the valve-casing 48 is a valve 53 the 100 object and function of which will appear later.

The rings 5 are shifted out of engagement with the casing 22 or into their open position by the following mechanism: Secured 105 to the outer portions of the ring 7 by means such for instance as eyes 54 is a flexible member such for instance as a wire or cord 55 which passes around pulleys 56, 57 and 58. The ring 7 on the open end of the 110 conduit 3 is shifted through the medium of a flexible member 59 which passes around pulleys 60, 61 and 62, and its free ends are connected with the ring 7. Secured to the pulleys 57 and 61 are flexible members 63 115 and 64 respectively, which wind up on a windlass 65 provided with a crank 66 within reach of the operator of the balloon. The valves 18 in the ends of the conduits 3 and 4 are opened through the medium of a flexible member such for instance as a wire or cable which extends from the valve 18 in the conduit 4 around pulleys 68, 69, 70, 71 and 72 to the valve in the conduit 3. The pulley 71 in turn is connected by means of 120 a flexible member 73 with a windlass 74 operated by means of a crank 75 within the grasp of the operator.

The operation of the device is as follows: Before going into a detailed description of 130

the operation of this device, it will be stated that the movements of the rings 5, when shifted into engagement with the rings 23 for closing the openings between the casing 22 and the ends of the conduits 3 and 4 are approximately simultaneous and both must be operated to accomplish the function of this device, that is to say, they are both shifted into their open positions or in their closed positions at the same time. Supposing that both of the bands 5 are in the position of the band 5 on the end of the conduit 4 in the right in Fig. 2 and the ends of the conduits 3 and 4 are spaced from the casing 22 and the valves 18 in position to prevent a fluid from passing through the radiator from the conduit 3 to the conduit 4, then the air from the outside will pass inwardly through the opening between the conduit 3 and the casing 22 into the casing 22 and from thence outwardly through the opening between the casing and the end of the conduit 4 so that the radiator is thereby cooled and the temperature of the gas in the balloon is not affected. Imagining this to be the situation, and it is desired to heat the gas in the balloon, the rings 5 are drawn into snug engagement with the rings 23 of the casing 22 to cause the ridges 10 to seat in the grooves 24 for effecting a fluid-tight joint, this being accomplished through the medium of the levers 20. The casing at this period is filled with normal atmospheric air and to flush this casing and to drive out the air therefrom, to prevent its being blown into the balloon, the valve is moved into the position shown in full lines in Fig. 1, so that the gas from the balloon will pass into the valve-casing 48 through the inlet 49 and from thence upwardly through the pipe 46 and downwardly into the casing above the diaphragms 31 and 32 which latter serve to distribute the gas more evenly and drive out the inclosed air downwardly through the perforated diaphragms 34 and 35 and out through the pipe 47 into the valve-casing 48 from which it escapes through the exhaust 50. When this has been accomplished, the windlass 34 is operated and the valves 18 opened and the gas is drawn downwardly from the balloon through the conduit 3 by the fan 45, and is forced through the radiator which beats it and from thence it passes outwardly around the valve 18 into the conduit 4 and finally into the balloon in a heated condition. When the gas in the balloon has been heated to a proper degree, the valves 18 are closed and the valve 53 turned to the position indicated in dotted lines and air under pressure is introduced through the pipe 51 by opening the check valve 52 which permits the air to pass from the pipe 51 upwardly through the valve into the pipe 47 and through the perforated diaphragms 34 and 35, driving the gas contained in the cas-

ing upwardly through the diaphragms 31 and 32 and outwardly through the pipe 46 into the valve-casing from whence it escapes through the outlet 50. After this has been effected, the bands 5 are shifted away from the bands 23 or into their open positions as shown in the right in Fig. 2 so that the air may pass inwardly from the opening adjacent to the end of the conduit 3, past the fan 45 and radiator 29 and outwardly through the opening between the casing 22 and the end of the conduit 4.

It will be noted that when the windlass 74 is released the valves 18 are automatically closed whenever the windlass is not employed, so that there is no escape of the gas through the open ends of the conduits 3 and 4.

I claim:

1. A balloon, a pair of conduits communicating with the interior thereof at different points, the opposite ends of said conduits opposing each other, a heat-generating instrumentality positioned between the ends of said conduits, means for shifting the ends of said conduits away from said heat-generating instrumentality, means for closing the ends of said conduits when separated from said heat-generating instrumentality to permit the latter to be used irrespective of said conduits.

2. A balloon, a pair of conduits leading from different portions of the interior thereof, the opposite ends opposing each other, valves in the ends for closing them, a heat-generating instrumentality positioned between the ends of said conduits, means for shifting the ends of said conduits toward and away from said heat-generating instrumentality, and means for driving a current of fluid through said heat-generating instrumentality.

3. In combination, a balloon, a pair of conduits leading from different points of said balloon, the opposite ends of said conduits opposing each other, rigid members secured on the ends of said conduits, a casing positioned between the rigid members on the opposing ends of said conduits, means for shifting said members into fluid-tight engagement with the ends of said casing, and a heat-generating instrumentality interposed on said casing.

4. In combination, a balloon, a pair of conduits leading from different points of said balloon, the opposite ends of said conduits opposing each other, rigid ring-forming members secured to the ends of said conduits, valves carried by said ring-forming members for closing the ends of said conduits, a casing interposed between said ring-forming member, means for shifting said ring-forming members into and out of engagement with said casing, a heat-generating instrumentality carried by said casing

and adapted to heat the interior of said balloon, and the fluid passing through said conduits when the ring-forming members are in their closed position and said valves 5 are open, said heat-generating instrumentality being also operative when said valves are closed and said ring-forming members are shifted away from said casing.

5. In combination, a balloon, a pair of 10 conduits leading from different points of said balloon, the opposite ends of said conduits opposing each other, rigid members secured to the opposing ends of said conduits, valves carried by said rigid members 15 for closing the ends of said conduits, a casing interposed between said rigid members, a heat-generating instrumentality carried by said casing, a fan for driving a fluid through said heat-generating instrumentality, means for shifting said rigid members into and out of snug engagement with 20 the ends of said casing, and a motor adapted to operate said fluid-driving means and furnish heat to said heat-generating instrumentality.

6. A device for heating the fluid within a balloon embodying a casing arranged to be interposed in a conduit leading to the interior of said balloon, a motor radiator positioned in said casing, a fan for driving a fluid through said radiator, a foraminous partition extending across said casing, pipes 30 communicating with said casing on opposite

sides of said partition, valve mechanism communicating with air under pressure and 35 the fluid under pressure in said balloon for alternately filling said casing either with air or the gas from the balloon.

7. A balloon, a pair of conduits communicating at different points with the interior 40 thereof, the ends of said conduits provided with rigid members, valves carried by said rigid members, a casing interposed between said rigid members, means to shift said rigid members into and out of engagement with 45 said casing, a heat-generating instrumentality positioned within said casing and arranged to heat the fluid passing through said conduits when the rigid members are in engagement with said casing and said valves 50 are open and adapted to be air-cooled when said valves are closed and the ends of said conduits separated from said casing to permit the entrance of outside air through the opening between one conduit and said casing and escaping through the opening between the end of the other conduit and said casing, substantially as shown and described.

In testimony whereof I have hereunto set my hand in presence of two subscribing witnesses.

RALPH HAZLETT UPSON.
